FILLING-FEELER MECHANISM.

1,249,281.

Specification of Letters Patent. Patented Dec. 4, 1917.

Application filed May 6, 1916. Serial No. 95,925.

To all whom it may concern:

Be it known that I, JONAS NORTHRUP, a citizen of the United States, residing at Hopedale, in the county of Worcester and

5 State of Massachusetts, have invented certain new and useful Improvements in Filling-Feeler Mechanisms; and I do hereby declare the following to be a full, clear, and exact description of the invention, such as 10 will enable others skilled in the art to which it appertains to make and use the same.

The present invention relates to an improvement in filling feeler mechanisms for looms.

15 One object of the present invention is to reorganize the construction of filling feeler mechanisms in order to produce a novel and simple form of filling feeler mechanism capable of determining critical or predetermined exhaustion of filling and causing all the filling carriers to be unwound or exhausted uniformly regardless of variations in their sizes and regardless of whether they are obliquely positioned in the shuttle.

20 A further object of the invention is to produce a filling feeler mechanism in which the filling feeling member or feeler is provided with filling engaging teeth of a novel construction, by virtue of which the filling 30 on that part of the filling carrier opposite the feeler may be entirely unwound or exhausted, or any desired numbers of layers of filling strands may be left thereon. Whether the filling engaging teeth shall per-

35 form the one mode of operation or the other is determined and controlled by the adjustment of the feeler relatively to the filling carrier. To the accomplishment of these objects the invention consists in the 40 improved filling feeler mechanism herein-after described and particularly pointed out in the claims.

In the accompanying drawings illustrating the preferred form of the invention, 45 Figure 1 is a plan view of the filling feeling end of a loom showing the application of the improved filling feeler mechanism thereto; Fig. 2 is a detail plan showing the positions of the parts of the filling feeler upon 50 predetermined exhaustion of filling; Fig. 3 is a section taken on the longitudinal axis of the filling feeler and its support; and Fig. 4 is an enlarged detail of the filling 55 feeling end of the feeler.

The loom to which the improved filling 55 feeler mechanism is applied may be of any usual or preferred construction, and may be either a plain loom, or a weft replenishing loom. If applied to a plain loom, the filling feeler mechanism operates upon critical or 60 predetermined exhaustion of filling to cause loom stoppage; and if applied to a weft replenishing loom, the filling feeler mechanism usually operates, upon critical exhaustion of filling, to cause the insertion of a fresh supply of filling in the shuttle. The loom illustrated in the drawings comprises a breast beam 10, a rock or change shaft 11 extending transversely of the loom and journaled in brackets secured to the front thereof, a weft 70 hammer 12, mounted for oscillatory movements under the filling fork 13, a lay 14, supported for movements toward and from the breast beam in timed relation with the reciprocations of the weft hammer, a shuttle 75 15 having the usual slot 16 in its front wall, and a filling carrier 17 held in the shuttle by the shuttle springs 18. If the filling feeler mechanism is applied to a plain loom, the change shaft is connected at the filling feeling end of the loom with loom stopping devices; and if the filling feeler mechanism is applied to a weft replenishing loom, the change shaft is connected at the end of the 80 loom opposite the filling feeler mechanism 85 with weft replenishing mechanism. The construction of these parts and their actuating means, and their mode of operation is well-known to those skilled in the art.

The improved filling feeler mechanism 90 comprises a filling feeling member or feeler 20, mounted for pivotal and reciprocatory movements on a feeler plate or support 21 secured by a bolt 22 passing through a slot 23 in the feeler plate to a bracket 24, the 95 bracket 24 being, in turn, secured by bolt and slot connections to another bracket 25 fastened to the breast beam. By means of these connections the operative position of the feeler 20 may be adjusted longitudinally, and transversely, and so, obliquely, relatively to the filling carrier. The feeler is provided with a slot 27 formed longitudinally of its length, the forward end of which engages a guide pin 28 fixed in the 100 feeler-plate 21 and rising vertically therefrom. A collar 29, surrounding the upper 105 end of the pin, prevents the vertical dis-

placement of the feeler. A contractile spring 30 of light tension, one end of which is secured to a pin 31 fixed in the forward end of the feeler and the other end of which is secured to the guide pin 28, tends to hold the feeler toward the filling carrier, as shown in Fig. 1, this being the normal position of the feeler. While the feeler is in this position, a shoulder 33, projecting laterally from the left-hand side of the feeler, is in engagement with a stop pin 34 rising from the feeler plate, and an arm 35, projecting laterally from the right-hand side of the feeler, is in engagement with a second stop pin 36 rising vertically from an extension 37 of the feeler plate.

It will be observed that the rearmost or filling feeling end of the feeler lies in a line drawn through the guide pin and disposed at right angles to the filling carrier while the feeler is in normal position. This line, then, is parallel to the reciprocations of the lay. It will be further observed that the strain of the contractile spring 30 lies along an extension of this line. Consequently, the spring 30 has no tendency to turn the feeler about the guide pin. When the filling carrier strikes the feeler on the filling feeling beat of the lay, this beat of the lay taking place when the shuttle is boxed at that end of the lay opposite the filling feeler mechanism; the pressure of the filling carrier against the feeler pushes it straight forward. The pressure of the filling carrier upon the filling feeling end of the feeler has therefore no tendency to turn the feeler about the guide pin. Accordingly, means, exclusive both of the pressure of the filling carrier upon the feeler and of the strain of the spring 30 upon the feeler, must be employed in order to give the feeler a pivotal movement, that is, a filling feeling movement.

The filling feeler mechanism is connected with the rock or change shaft 11 through loom controlling devices comprising an arm 38, fixed to the change shaft and projecting upwardly therefrom, a lever 39, pivoted at the upper end of the arm 38, and a latch lever 40 pivoted on a vertical pin 41 fixed in the rearward end of the lever 39. The connections between the filling feeler mechanism and the loom controlling devices consist of a link 42, the left-hand end of which is received in an open slot 43 in the forward end of the feeler, the right-hand end of the link being loosely received in a hole in the head of an adjustment screw 44 threaded in the forward end of the latch lever 40. By disconnecting the link from the slot 43 and turning the screw in the latch lever, the interrelation of the feeler and the latch lever may be adjusted. Upon critical exhaustion of filling, a notch 45, formed on the rearmost end of the latch lever, is adapted to be engaged by a bunter 46 secured to the weft

hammer 12, and to be pushed forward by it, thereby oscillating the change shaft to stop the loom or to set in operation the weft replenishing mechanism. A lightly tensioned compression spring 47, interposed between the rearmost end of the lever 39 and the adjacent side of the rearward end of the latch lever, tends to swing the notch bearing end of the latch lever into the path of motion of the bunter. The operative position of the latch lever is determined by the engagement of a stop lug 48 projecting laterally from the forward end of the latch lever, with the adjacent side of the lever 39. It will be observed that, by reason of the engagement of the arm 35 with the stop pin 36, while the feeler is in normal position, a pull of considerable force may be exerted upon the link 42 in a right-hand direction without swinging the feeler about its guide pin. But when on the forward beat of the lay and the engagement of the filling with the filling feeling end of the feeler, the feeler is moved forward out of engagement with its stop pins, the compression spring 47, acting through the latch lever and the link, tends to swing the feeler about its guide pin so as to move the filling feeling end of the feeler toward the butt of the filling carrier in its filling feeling movement. So long as the filling has not been exhausted to a predetermined extent, the coöperation of the filling with the filling engaging teeth (with which the filling feeling end of the feeler is provided) prevents this pivotal movement of the feeler; and consequently prevents the notch bearing end of the latch lever from moving into the path of motion of the bunter. When the filling has been critically exhausted, however, the compression spring 47 is permitted to swing the filling feeling end of the feeler toward the butt of the filling carrier and to swing the notched end of the latch lever into the path of the bunter 46.

Upon the rearmost or filling feeling end of the feeler are formed filling engaging teeth. By an inspection of Fig. 4 it will be seen that the individual teeth of the left-hand section 50 are acute angled, like the teeth of a rip saw, with their apexes pointed leftwardly, that is, toward the butt of the filling carrier, and that the individual teeth of the right-hand section 51 are right or dull angled, like the teeth of a cross cut saw. The right-angled teeth 51 extend beyond the acute angled teeth 50 toward the filling carrier a distance equal to the thickness of two or three strands of filling. It is obvious that if, during the filling feeling movement of the feeler toward the butt of the filling carrier, the acute angled teeth engage the filling, the filling feeling movement will be arrested and that, on the contrary, the engagement of the right-angled teeth alone with the filling will not arrest the filling

feeling movement of the feeler, because these latter teeth will ride over the filling strands. It is apparent that acute angled teeth could be substituted for and perform the function 5 of the right-angled teeth if their apexes were directed toward the tip of the filling carrier. By reason of the difference in form between the two sections of filling engaging teeth it is possible to secure a difference of result in 10 critically exhausting the filling. If it is desired to completely exhaust the filling from that part of the filling carrier opposite the feeler, the feeler is adjusted so that the acute angled teeth are in alinement with (or project beyond) the right-angled teeth with respect to the filling carrier. But if it is desired that a number of strands of filling should be left on the filling carrier after critical exhaustion, the feeler will be adjusted 15 so that the right-angled teeth extend toward the filling carrier beyond the acute angled teeth a distance equal to the thickness of the number of filling strands to be left on the carrier.

20 The possibility of securing this diversity of result will be made clear from a consideration of the mode of operation of the filling feeler mechanism. Assuming that complete exhaustion of the filling from that part of the filling carrier opposite the feeler is desired, leaving on the carrier only the customary "preliminary bunch" of filling: To secure this result the feeler is adjusted as described. On each filling feeling beat 25 of the lay, and the consequent disengagement of the feeler from its stop pins, the spring 47 tends to swing the feeler about its guide pin and thereby move the filling feeling end of the feeler toward the butt of the filling carrier. So long as the acute angled teeth 50 engage any filling, the filling feeling movement is arrested, so that, before the feeler can have any pivotal movement, the filling on the carrier opposite the feeler 30 must be completely unwound, exposing the surface of the carrier. Then, as the filling continues to unwind, the spring 47 causes the filling feeling end of the feeler to travel along the unwound surface of the carrier 35 toward the carrier butt, and, at the same time, swings the notch 45 toward the path of motion of the bunter 46. These movements are arrested by the engagement of the acute angled teeth with the end winding 40 of the filling until, finally, when the filling has been unwound to a predetermined point from the butt end of the filling carrier, the notch 45 is in the path of motion of the bunter and the bunter on its forward beat 45 pushes the latch lever forward and sets in operation the loom controlling devices.

Assuming now that it is desired to leave several strands of filling on the filling carrier, as would be the case if the carrier were 50 wound without the "preliminary bunch", the feeler is first adjusted so that the right-angled teeth 51 are advanced toward the filling carrier beyond the acute angled teeth a distance equal to the thickness of the number of strands of filling it is desired should 55 remain on the carrier. So long as more strands of filling than the predetermined number remain on the carrier, the acute angled teeth will engage them on the filling feeling beat of the lay and prevent the 60 spring 47 from swinging the feeler about its guide pin; but when the filling has become so far exhausted that there remains on that part of the carrier opposite the feeler a thickness of filling equal to the difference 65 in distance of the two sections of teeth from the carrier, the right-angled teeth will penetrate the mass of filling so as to be struck by the filling carrier, and the acute angled teeth will not engage any filling. Consequently, when the feeler is pushed forward by the carrier, the spring 47 will impart a filling feeling movement to the feeler toward the butt of the carrier, the right-angled teeth riding over the filling strands, the light 70 tension of the spring 30 readily permitting this riding action. As the filling feeling end of the feeler moves toward the butt of the carrier, the end windings of the layers superposed upon the predetermined number 75 of filling layers are engaged by the acute angled teeth and the filling feeling movement is prevented until these superposed layers are unwound to a predetermined point from the carrier butt. When this point is reached 80 by the acute angled teeth, the notch 45 is in the path of the bunter and a change in the operation of the loom is effected.

By reason of the reciprocal motion of the feeler, variations in the sizes of the filling carriers do not affect the accuracy of the filling feeling operation; and for the same reason an obliquely positioned filling carrier has no effect upon the accuracy in determining critical exhaustion of filling; so that 85 filling carriers, regardless of variations in size and position, are exhausted until the filling on that part of the carrier opposite the feeler has been unwound to a predetermined extent, and that, thereafter, the filling 90 is unwound until the filling engaging end of the feeler reaches a predetermined point from the butt of the filling carrier. It is thus seen that all the filling carriers must be exhausted to a uniform and predetermined extent.

The novel form of filling engaging teeth has been described as employed in connection with a particular form of filling feeler mechanism. It is obvious, however, that these filling engaging teeth may be applied 95 to other filling feeler mechanisms.

Having thus described the invention, what is claimed is:

1. A loom having, in combination, loom 100

- controlling devices, and a filling feeler mechanism comprising a stationary support, a feeler mounted directly upon the support for pivotal and reciprocatory movements, means 5 for imparting a reciprocatory movement to the feeler in one direction, and connections between the feeler and the loom controlling devices, said loom controlling devices having provision for imparting a pivotal movement to the feeler. 10
2. A loom having, in combination, a weft hammer, loom controlling devices, a latch lever connected therewith, a filling feeler mechanism comprising a fixed support, a filling feeler mounted directly on the support having provision for reciprocatory and swinging movements relatively to the support, means for yieldingly pressing the feeler toward the lay, a link connecting the feeler with the latch lever, means tending to swing the feeler and the latch lever to bring the latter into the path of the weft hammer, and means for preventing the swinging movement until the filling has been engaged by the filling carrier, whereupon the swinging movement is prevented by the filling until it has been exhausted to a predetermined extent. 15
3. A loom having, in combination, a lay, a filling carrier, and a filling feeler mechanism comprising a stationary feeler support, a guide pin fixed thereon, a feeler having an elongated slot for engaging the guide pin, stop pins on the support, yielding connections between the support and the feeler for normally holding the feeler against the stop pins, and means tending to impart a pivotal movement to the feeler, said stop pins being arranged to prevent the pivotal movement 20 of the feeler so long as the latter is not engaged by the filling carrier. 25
4. A loom having, in combination, loom controlling devices, and a filling feeler, mechanism comprising a feeler, a feeler support, a guide pin fixed thereon for guiding the movements of the feeler, means for imparting a reciprocatory movement to the feeler, and connections between the loom controlling devices and the feeler, said loom controlling devices having provision for imparting a pivotal movement to the feeler. 30
5. A loom having, in combination, a lay, a filling carrier, and a filling feeler mechanism comprising a stationary support, a feeler mounted directly thereon for reciprocatory and pivotal movements, means for imparting a reciprocatory movement to the feeler in one direction, and means for imparting the pivotal movement to the feeler when the filling has been exhausted to a predetermined extent. 35
6. A loom having, in combination, a lay, a filling carrier, and a filling feeler mechanism comprising a stationary support, a feeler mounted directly thereon for reciprocatory and pivotal movements constructed and arranged so that the pressure of the filling carrier upon it imparts only a reciprocatory movement to it and in one direction, means to impart a reciprocatory movement to the feeler in the opposite direction, and means operating when the filling has been exhausted to a predetermined extent to impart a pivotal movement to the feeler. 40
7. A loom having, in combination, a lay, a filling carrier, and a filling feeler mechanism comprising a stationary support, a guide pin fixed thereon, stop pins on the support, a feeler mounted for reciprocatory and pivotal movements relatively to the support and having provision for engaging the guide pin, means for normally holding the feeler against the stop pins so that the filling feeling end of the feeler and the guide pin lie on a line parallel with the path of motion of the lay, and means operating on the filling feeling beat of the lay and on critical exhaustion of filling to impart a pivotal movement to the feeler, said stop pins preventing the pivotal movement of the feeler until the engagement of the filling carrier with the feeler disengages the feeler from the stop pins. 45
8. A loom having, in combination, a filling carrier, and a filling feeler mechanism comprising a support, a feeler mounted thereon, means for imparting a filling feeling movement to the feeler, and two sections of filling engaging teeth on the feeler, one section of teeth being formed for preventing the filling feeling movement of the feeler while it is in engagement with the filling, and the other section of the teeth being formed to permit the filling feeling movement of the feeler while it is in engagement with the filling. 50
9. A loom having, in combination, a lay, a filling carrier, and a filling feeler mechanism comprising a feeler, means for imparting a filling feeling movement to the feeler, and filling engaging teeth on the feeler, a portion of the teeth being acute angled with their apexes toward the butt of the filling carrier, and a portion of the teeth being dull angled. 55
10. A loom having, in combination, a lay, a filling carrier, and a filling feeler mechanism comprising a feeler, means for imparting a filling feeling movement to the feeler, and filling engaging teeth on the feeler, a portion of the teeth having their apexes directed toward the butt of the filling carrier, and a portion of the teeth having their apexes directed another way than toward the butt of the filling carrier. 60
11. A loom having, in combination, a lay, a filling carrier, and a filling feeler mechanism including a feeler having two sections

of filling engaging teeth, the teeth of one section extending beyond the teeth of the other section toward the filling carrier a distance equal to the depth of the strands of 5 filling to be left on the filling carrier.

12. A loom having, in combination, a lay, a filling carrier, and a filling feeler mechanism including a feeler and means for turning the feeler, said feeler having filling 10 gaging teeth, a portion of said teeth having their sides sloping in the direction in which the feeler turning means acts, and a portion of said teeth having their sides sloping in a direction other than that in which the feeler 15 turning means acts.

13. A loom having, in combination, a lay, a filling carrier, and a filling feeler mechanism comprising a stationary feeler support, a feeler mounted directly thereon for 20 reciprocatory and pivotal movements, and means to impart a pivotal movement to the feeler, said means being ineffective to swing the feeler before engagement of the feeler with the filling carrier, and being effective 25 to swing the feeler when the latter is carried forward by the filling carrier and the filling has been exhausted to a predetermined extent.

14. A loom having, in combination, a lay, 30 a filling carrier, and a filling feeler mechanism comprising a stationary feeler support, a feeler mounted thereon for reciprocatory and pivotal movements, a guide pin fixed on the support for engaging and controlling 35 the movements of the feeler, means tending to hold the feeler in normal position toward the filling carrier, and means tending to impart a pivotal movement to the feeler, said latter means being ineffective until the feeler 40 has been carried forward by the filling carrier and the filling thereon has been exhausted to a predetermined extent.

15. A loom having, in combination, a lay, 45 a filling carrier, and a filling feeler mechanism comprising a stationary feeler support, a guide pin fixed thereon, a feeler in engagement with the guide pin adapted to have a forward movement by engagement with the filling carrier, means to impart a 50 movement to the feeler in the opposite direction, and means operating upon the forward movement of the feeler to impart a pivotal movement to the feeler when the

filling has been exhausted to a predetermined extent.

16. A loom having, in combination, a lay, 55 a filling carrier, and a filling feeler mechanism comprising a stationary feeler support, a guide pin fixed on the support, a feeler having a slot in engagement with the guide pin so that the feeler may have reciprocatory and pivotal movements, means tending to hold the feeler in normal position toward the filling carrier, and means operating to impart a pivotal movement to 60 the feeler after the feeler is moved forwardly and on critical exhaustion of filling.

17. A loom having, in combination, a lay, 65 a filling carrier, and a filling feeler mechanism comprising a stationary support, a 70 guide pin fixed on the support, a feeler having a slot engaging the pin so that the feeler may have movement toward and from the lay on a straight line so long as the filling has not been exhausted to a predetermined 75 extent, and means to impart a movement to the feeler other than on the straight line when filling has been exhausted to a predetermined extent.

18. A loom having, in combination, a lay, 80 a filling carrier, and a filling feeler mechanism comprising a stationary support, a feeler mounted directly thereon for movement forward on a straight line by the filling carrier, means to swing the feeler, and 85 means to prevent the swinging of the feeler until it has been moved by the filling carrier, whereupon said swinging movement is prevented by the filling until the latter has been exhausted to a predetermined extent. 90

19. A loom having, in combination, loom controlling devices, and a filling feeler mechanism comprising a feeler support, a filling feeler having provision for reciprocatory and pivotal movements relatively to 95 the feeler support, means fixed on the support for guiding the reciprocatory and pivotal movements of the filling feeler, means for imparting the reciprocatory movements to the filling feeler, means for moving the 100 filling feeler pivotally when the filling has been exhausted to a predetermined extent and connections between the loom controlling devices and the filling feeler.

JONAS NORTHRUP.
